STEMMING DUMMY FOR SHOOTING COAL

Frank Yakes, Jr., Lafayette, Colo.

Application March 29, 1940, Serial No. 326,594

9 Claims. (Cl. 102—11)

This invention relates to a stemming dummy for blasting operations and, while not limited thereto, is more particularly designed for use in breaking coal in coal mines.

The usual coal shooting operation consists of drilling or boring a shot hole into the coal. These shot holes are of considerable depth, often up to twenty feet. The powder, dynamite, or other explosive or expanding material is then placed in the hole and forced to the far extremity thereof. The hole is then packed with material completely to the breech. This packing is usually accomplished by placing stemming dummies or clay cartridges in the hole and tamping or packing them compactly therein to prevent the force of the explosion from blowing from the shot hole.

Such a method requires considerable time to properly pack the stemming dummies in place and it also results in confining the force of the explosion to the immediate area around the explosive. This concentration of the explosive action results in shattering and powdering the coal for a considerable area around the explosion and this shattered and powdered coal is valueless.

The principal object of this invention is to provide a mechanically operated stemming dummy which can be inserted into the open end of the shot hole and quickly locked in place therein to prevent the force of the explosion from blowing from the hole.

One advantage of the improved stemming dummy is the entire length of the hole is used as an expansion chamber so that the force of the explosion is distributed throughout the entire length thereof to give a long uniform expanding action which will break down the coal in large chunks without the formation of fines or dust.

Another advantage is that the time required to place the usual stemming dummies in position is greatly reduced and the cost of the stemming dummies, which in the old system are entirely destroyed at each shot, is eliminated for the improved mechanical stemming dummy can be used over and over again repeatedly.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like nu-

mers refer to like parts in all views of the drawing and throughout the description.

In the drawing:

Fig. 1 is a side view of the improved stemming dummy.

Fig. 2 is a longitudinal section therethrough, taken on the line 2—2, Fig. 1.

Fig. 3 is a diagrammatic, vertical, sectional view through a typical coal seam, illustrating the position of the improved stemming dummy in a shot hole therein.

Fig. 4 is a detail cross section, taken on the line 4—4, Fig. 2.

The improved stemming dummy consists of a cylindrical shank portion 10 terminating at one extremity in a receiving socket 11 and at its other extremity in a pressure flange 12. A threaded draw bolt 13 extends throughout the length of the shank 10 and projects from both extremities thereof. A tubular nut 14 having wrench faces 15 is threaded on the threaded extremity of the draw bolt and serves to clamp a cross-shaped pressure plate 16 against the pressure flange 12 of the shank. The arms of the pressure plate are provided with pointed fangs 17.

The other extremity of the draw bolt is provided with a head 18 which rides against an internal shoulder in sleeve member 19. The sleeve member is provided with inclined openings 20 which are directed towards the head 18. A pointed head member 21 is threaded on the sleeve member 19 and closes the outer extremity thereof. A socketed ferrule 22 is placed upon the inner extremity of the sleeve member which is shouldered to receive it. The socketed extremity of the ferrule and the receiving socket 11 on the shank 10 are of the same diameter and both have a larger diameter than the shank, sleeve and head portions.

An expandable rubber sleeve 23 is placed about the draw bolt between the receiving socket 11 and the ferrule 22. The rubber sleeve may be provided with end washers 24 if desired.

In Fig. 3 a typical coal seam is indicated at 25 in which a shot hole 26 has been drilled. An explosive charge 27 is indicated in place in the hole at 27 with its electric ignition wires protruding therefrom at 28. In use, the stemming dummy is forced in the hole sufficiently far to cause the sharpened fangs 17 to enter the face of the coal about the hole 26, as illustrated in Fig. 3. The wires 28 pass from the hole through one of the spaces between the arms of the cross-shaped pressure plate.

The nut 14 is now rotated to pull the draw bolt outwardly. The draw bolt cannot rotate with the nut due to the fact that it is provided with a longitudinally extending keyway 29 into which a key 30, formed in the pressure plate 16, extends. The pressure plate cannot rotate since the prongs are engaged in the coal face.

The bolt pulls the ferrule 22 against the rubber sleeve causing it to expand transversely against the walls of the shot hole with sufficient force to prevent the dummy from being blown from the hole by the force of the explosion. It will be noted that the entire interior of the hole is open.

The shot is now fired and the force of the explosion acts throughout the entire interior of the hole to break down the coal throughout the entire length of the hole without wasteful shattering and powdering. It has been found that 20% less powder is necessary to produce the same or better breakdown than with ordinary tamped stemming.

After the shot is fired the dummy is recovered from the fallen coal for reuse in another hole.

It is desired to call attention to the advantages of the relatively long, tubular nut 14. The nut protects the threads from damage at all times. The threads never project into the open at any time. The long nut with the wrench faces at the outer end is receivable in the chuck of an electric or air drill, with which most mines are provided for driving the auger bits and setting up nuts and bolts. The power drill can therefore be used for tightening the nut 14 and expanding the dummy.

The head member 21 receives the brunt of the explosion and may be eventually worn away but it can be easily removed and replaced. It also allows easy access to the bolt for renewals and repairs. It will be noted that the force of the explosion against the head member is not transmitted to the draw bolt but is carried directly against the resilient sleeve 23 to still further expand and increase the holding capacity of the latter.

It was found by actual use of the invention under practical operating conditions that the stemming dummy would be thrown backward by the force of the explosion with the breaking coal. This did not appear to interfere with the efficiency of the breaking action but in order to reduce the force of this back throw, to avoid damage to the dummy, the inclined openings 20 were placed in the sleeve member 19.

The exact action of these openings is not fully understood but it was found that they practically eliminated all backthrow and the dummy simply falls with the coal at the point of use. It may be that the initial force of the explosion forces the sleeve down along the draw bolt against the resilient sleeve. This force might tend to throw the dummy backward, but immediately the blast enters into the hollow interior of the sleeve and head through the openings 20 creating instantaneous pressure therein which snaps the sleeve forward under the head of the bolt to jerk the entire assembly back into place.

The point on the head member acts to spread the outwardly moving gases against the walls of the hole while the improved stemming dummy has been particularly designed, and successfully used, for coal breaking work, it may be used wherever the material being broken is sufficiently fragile to break before ejecting the dummy.

While a specific form of the improvement has been described and illustrated herein, it is de-

sired to be understood that the same may be varied, within the scope of the appended claims, without departing from the spirit of the invention.

Having thus described the invention, what is claimed and desired secured by Letters Patent is:

1. An elongated stemming dummy for insertion in blasting shoe holes for sealing the latter against the force of an explosion comprising: a pressure plate for positioning over and about a shot hole; a draw bolt extending through said plate into said hole; an inner member on said draw bolt; a shank member extending inward from said plate toward said inner member; a resilient, longitudinally-compressible, laterally-expansive member about said bolt between the inner member and the shank member; a nut on said bolt exteriorly of said plate for drawing the inner member against the resilient member; and means for preventing rotation of the bolt in the pressure plate.

2. An elongated stemming dummy for insertion in blasting shot holes for sealing the latter against the force of an explosion comprising: a pressure plate for positioning over and about a shot hole; a draw bolt extending through said plate into said hole; an inner member on said draw bolt; a shank member extending inward from said plate toward said inner member; a resilient, longitudinally-compressible, laterally-expansive member about said bolt between the inner member and the shank member; a nut on said bolt exteriorly of said plate for drawing the inner member against the resilient member; and means for preventing rotation of the bolt in the pressure plate; and means for preventing rotation of said plate with reference to the axis of said hole.

3. An elongated stemming dummy for insertion in blasting shot holes for sealing the latter against the force of an explosion comprising: a pressure plate for positioning over and about a shot hole; a draw bolt extending through said plate into said hole; an inner member on said draw bolt; a shank member extending inward from said plate toward said inner member; a resilient, longitudinally-compressible, laterally-expansive member about said bolt between the inner member and the shank member; a nut on said bolt exteriorly of said plate for drawing the inner member against the resilient member; a keyway in said bolt; and a key projecting from said plate into said keyway to prevent rotation of said bolt in said pressure plate.

4. An elongated stemming dummy for insertion in blasting shot holes for sealing the latter against the force of an explosion comprising: a pressure plate for positioning over and about a shot hole; a draw bolt extending through said plate into said hole; an inner member on said draw bolt; a shank member extending inward from said plate toward said inner member; a resilient, longitudinally-compressible, laterally-expansive member about said bolt between the inner member and the shank member; a nut on said bolt exteriorly of said plate for drawing the inner member against the resilient member; means for preventing rotation of the bolt in the pressure plate; and fangs projecting from said pressure plate into the wall material about said hole to prevent rotation of said plate about the axis of said hole.

5. An elongated stemming dummy for insertion in blasting shot holes for sealing the latter

against the force of an explosion comprising: a tubular shank member; a headed, threaded bolt passing through said shank member and extending from both extremities thereof; a pressure plate against one end of said shank member of a size to extend outwardly beyond the diameter of said hole; a tubular nut on the threaded extremity of said bolt clamping said plate against said shank; a cylinder of compressible material about said bolt against the other end of said shank; and an inner member on the headed extremity of said bolt for compressing said resilient member against said shank.

6. An elongated stemming dummy for insertion in blasting shot holes for sealing the latter against the force of an explosion comprising: a tubular shank member; a headed, threaded bolt passing through said shank member and extending from both extremities thereof; a pressure plate against one end of said shank member of a size to extend outwardly beyond the diameter of said hole; a tubular nut on the threaded extremity of said bolt clamping said plate against said shank; a cylinder of compressible material about said bolt against the other end of said shank; a sleeve member about the headed extremity of said bolt, the latter resting against a shouldered recess therein; and a head member closing the inward extremity of said sleeve member.

7. An elongated stemming dummy for insertion in blasting shot holes for sealing the latter against the force of an explosion comprising: a tubular shank member; a headed, threaded bolt passing through said shank member and extending from both extremities thereof; a pressure plate against one end of said shank member of a size to extend outwardly beyond the diameter of said hole; a tubular nut on the threaded extremity of said bolt clamping said plate against said shank; a cylinder of compressible material about said bolt against the other end of said shank; a sleeve member about the headed ex-

tremity of said bolt, the latter resting against a shouldered recess therein; and a head member closing the inward extremity of said sleeve member, there being openings in said sleeve member to allow gases to pass to the interior thereof.

8. An elongated stemming dummy for insertion in blasting shot holes for sealing the latter against the force of an explosion comprising: a tubular shank member; a headed, threaded bolt passing through said shank member and extending from both extremities thereof; a pressure plate against one end of said shank member of a size to extend outwardly beyond the diameter of said hole; a tubular nut on the threaded extremity of said bolt clamping said plate against said shank; a cylinder of compressible material about said bolt against the other end of said shank; a sleeve member about the headed extremity of said bolt, the latter resting against a shouldered recess therein; and a head member closing the inward extremity of said sleeve member; and a ferrule in said sleeve member for receiving the inner extremity of said cylinder of compressible material.

9. An elongated stemming dummy for insertion in blasting shot holes for sealing the latter against the force of an explosion comprising: a tubular shank member; a headed, threaded bolt passing through said shank member and extending from both extremities thereof; a pressure plate against one end of said shank member of a size to extend outwardly beyond the diameter of said hole; a tubular nut on the threaded extremity of said bolt clamping said plate against said shank; a cylinder of compressible material about said bolt against the other end of said shank; and an inner member on the headed extremity of said bolt for compressing said resilient member against said shank; pointed fangs on said pressure plate for preventing rotation thereof in said hole; and means for preventing rotation of said bolt in said pressure plate.
